United States Patent Office

Des. 191,004
Patented Aug. 1, 1961

191,004

TABLE CENTER PIECE

Charles Morris, 401 Ocean Ave., Santa Monica, Calif.

Filed Aug. 22, 1960, Ser. No. 61,834

Term of patent 7 years

(Cl. D44—24)

I claim:

The ornamental design for a table center piece, substantially as shown.
